SOLAR HEAT STORAGE TRAY

James L. Schoenfelder, Iowa City, Iowa, and John H. McLaughlin, Elkhorn, Nebr., assignors to Solar, Inc., Mead, Nebr.

Filed Mar. 22, 1976, Ser. No. 669,191

Term of patent 14 years

Int. Cl. D23—03

U.S. CL. D23—127

FIG. 1 is a plan view of the solar heat storage tray of this invention.

FIG. 2 is an elevated frontal view of the tray of FIG. 1 as viewed along line 2—2.

FIG. 3 is an elevated side view of the tray of FIG. 1 along line 3—3.

FIG. 4 is an elevated rear view of the tray of FIG. 1 as viewed along line 4—4 of FIG. 1.

FIG. 5 is an elevated side view of the tray of FIG. 1 along line 5—5 of FIG. 1.

FIG. 6 is an elevated view of the tray of FIG. 1 as viewed along diagonal line 6—6.

FIG. 7 is an elevated view of the tray of FIG. 1 as viewed along diagonal line 7—7.

FIG. 8 is a view of the bottom side of the tray of FIG. 1 as viewed along line 8—8 of FIG. 2.

We claim:

The ornamental design for a solar heat storage tray, substantially as shown and described.
